REEL FOR FILM OR THE LIKE

Sam Pandolfo III, P.O. Box 8369, Denver, Colo.

Filed May 14, 1962, Ser. No. 70,131

Term of patent 14 years

(Cl. D61—1)

Fig. 1

Fig. 2

Fig. 3

I claim:

The ornamental design for a reel for film or the like, as shown.
